UNITED STATES PATENT OFFICE.

MARTHA E. SANTO, OF MOUNTAIN VIEW, CALIFORNIA.

IRONING BOARD.

Application filed June 23, 1924. Serial No. 721,904.

To all whom it may concern:

Be it known that I, MARTHA E. SANTO, citizen of the United States, residing at 325 Pettis Avenue, Mountain View, in the county of Santa Clara and State of California, have invented certain new and useful Improvements in Ironing Boards, of which the following is a specification.

My invention relates to improvements in ironing-boards which can be made either as a single ironing-board or as a multiple.

Referred to more particularly, my boards are each hinged at the inner end, each rests against solid bearings when in position for ironing, each can be upended out of the way after use and held in that position until pulled down again to the horizontal position of service.

In closer detail the improvement relates to a turret member, which in the case of my multiple ironing-board is turnable upon a central axis and lockable at certain positions of circular swing in same plane as the floor.

It further relates to a hinged member or pivotal-clamp for attaching the boards proper to the turret member above mentioned, and to certain alignment-bearings, pivots and abutments which by their co-action automatically provide stability for the boards against the jars and shocks of ironing.

The general object of my invention is to provide an ironing-board apparatus that will give greater efficiency than has heretofore been provided in the art; which I attain by a valuable saving in time, in space, in labor, and by the provision of certain new and useful combinations of the parts which carry out the purpose of the invention.

A specific object of the invention, as indicated, is to provide ironing-boards that can be tilted up when not in use, which feature not only saves space but, in the case of laundries whose floors are frequently scrubbed or hosed out, saves the ironing-board coverings from being soiled and spattered.

Another object of tilting the boards up when not in use is that the coverings tend to tighten on the boards when in that position rather than to slip off as is frequently the case where the boards hang taper-end down.

A further object is to provide a pivotally-hinged socketed-clamp adapted to carry the boards and admit of their ready insertion or removal therefrom; said clamp provided

with an abutment member and an alignment member to resist downward or side pressures when ironing.

Another object is to provide a turret member adapted to carry a number of ironing-boards of different shapes and sizes, turnably mounted for selection by an operator, said turret provided with means to lock it against circular movement at given points, and further provided with means to regulate its height from the floor, provided also with an adjustable collar adapted to carry, removably, an iron-stand and cups for dampening.

A further object is to provide a retaining means for securing the boards when upended: and other objects which will appear.

The invention consists in the combination and arrangement of parts hereinafter described, shown in the drawings and pointed out in the appended claims.

In said drawings:

Fig. 1, is an elevation of the ironing-board apparatus embodying my invention.

Fig. 2, shows a vertical section through the turret approximately on the lines II—II of Fig. 3.

Fig. 3 shows a plan view of the turret.

Fig. 4, shows a plan view of the pivotal socketed-clamp.

Fig. 5, is an edge-view of the socket-end of one of the boards carrying butt-plate for vise-screw.

Fig. 6, is a horizontal sectional view taken on line VI—VI of Fig. 1.

Fig. 7, is a fragmentary sectional view taken on lines VII—VII of Fig. 1.

Fig. 8, is a detail elevational view of the pivot-shaft.

Similar numerals refer to similar parts throughout the several views. Fig. 1, displays my improved ironing-board standing on a floor. The stand 1 carries, in true axial alignment therewith, pivot-shaft 2 which is held stationary by means of set-screw 3 which also admits of height regulation for the pivot-shaft 2 with respect to the floor.

Above the stand 1, a slip-fit on the shaft 2, is the collar 6 forming one member of a hook-and-socket joint adapted to co-act with its complement as shown at 7 in Fig. 1.

Fig. 6, shows a plan of collar 6 in engagement with the combination iron-stand 4 and dampener cups 5 and 5', which combination may be removed bodily from the collar

6 by lifting up the outer end of the iron stand 4 and pulling it away; the collar 6 being also provided with a set-screw 26 which will hold it at any point on the pivot-shaft 2 within the limits between top of the stand 1 and the bottom of the turret 8.

The turret 8 as shown in Fig. 3, has the four supporting arms 21 but obviously could be made with more arms or less; said arms 10 21 are drilled at the upper end to receive bolt 11 which passes through the lugs 10 of housing-clamp 9 (Fig. 4) thus forming a hinged or pivotal connection between turret 8 and socketed-clamp 9. Said socketed-clamp 9 has various parts and functions. The lugs 10 form one member of the pivotal point for turning the boards up or down. The groove 22 in the inner end of the socketed-clamp 9 registers alignment of the 15 20 clamp 9 when inter-meshed with arcuate rib 23, whereas its contact with the under side of turret 8 at 16, Fig. 2 forms a positive abutment to resist down pressures when ironing; turret 9 also carries retaining-spring 13 which when engaged with rib 23 serves to maintain the board in its end up position until smartly pulled upon to release it.

Turret 8 is centrally bored and recessed to be a working fit for pivot-shaft 2 with 30 its flanged head 14 which may then be slipped into the turret 8 and the cap 24, also a working fit for head 14, screwed in place thus mounting the turret 8 turnably upon the pivot-shaft 2, with a lubricating means 35 at 17.

Head 14 is provided with holes 20 as clearly indicated in Figs. 2, 3 and 8. The cap 24 is furnished with detent 19 adapted to register with any one of holes 20 to 40 arrest circular movement of turret 8 and to hold it stationary when in use.

The method of operation of my invention is obvious: Assuming that the multiple ironing-board is assembled and ready for 45 use with all its various boards end up. The operator can now select the board needed, which if not in position can be swung round to the right place by releasing detent 19 and letting it fly back into the next registering 50 hole 20, which will lock the turret 8 against circular movement.

With the selected board now standing in the right place to be lowered an outward pull on its upper end will release retaining-spring 13 from rib 23, while the board is being lowered it pivots on bolt 11 and groove 22 describes an arc inmeshed with 55 23. The abutment of the socketed-clamp 9 against the turret 8 at 16 automatically brings the board into position for ironing without further adjustment.

I am aware that prior to my invention multiple ironing-boards have been made in connection with a turnable carrier and stand. I therefore do not claim such a combination broadly; but—

I claim—

1. An ironing board stand including a support, an arcuate arm extending downwardly and outwardly from said support, an arm extending upwardly from the lower end of the arcuate arm and inclined inwardly with relation thereto, a transverse pivot located at the upper end of the last mentioned arm concentric to the arcuate arm, a socket for receiving an ironing board and provided with downwardly extending lugs mounted on said pivot, the said socket being movable between horizontal and inwardly and upwardly inclined positions, and an ironing board having one end received in said socket. 70 75

2. An ironing board stand including a support, an arcuate arm extending downwardly and outwardly from said support, an arm extending upwardly from the lower end of the arcuate arm and inclined inwardly with relation thereto, a transverse pivot located at the upper end of the last mentioned arm concentric to the arcuate arm, a socket for receiving an ironing board and provided with downwardly extending lugs mounted on said pivot, the said socket being movable between horizontal and inwardly and upwardly inclined positions, an ironing board having one end received in said socket, and a stop against which the socket engages upon the ironing board being moved to horizontal position and against which the board engages upon being raised. 90 95

In testimony whereof I affix my signature.

MARTHA E. SANTO.
